UNITED STATES PATENT OFFICE

DAVID A. SMART, OF CHICAGO, ILLINOIS

DESIGN FOR A DESK

Application filed June 18, 1930. Serial No. 36,087. Term of patent 7 years.

To all whom it may concern:

Be it known that I, DAVID A. SMART, a citizen of the United States, residing at Chicago, in the county of Cook and State of Illinois, have invented a new, original, and ornamental Design for a Desk, of which the following is a specification, reference being had to the accompanying drawing, forming a part hereof.

In the illustration,
Fig. 1 is a perspective view of a desk, showing my new design;
Fig. 2 is a front elevation of the desk;
Fig. 3 is an end elevation of the desk; and
Fig. 4 is a plan view of the desk.

What I claim is:

The ornamental design for a desk, as shown.
DAVID A. SMART.
